UNITED STATES PATENT OFFICE.

AUGUST F. KRAEMER, OF PROVIDENCE, RHODE ISLAND, ASSIGNOR, BY DIRECT AND MESNE ASSIGNMENTS, OF ONE-HALF TO LOUIS STERN COMPANY, OF PROVIDENCE, RHODE ISLAND, A CORPORATION OF RHODE ISLAND, AND ONE-HALF TO HIPP DIDISHEIM CO., INC., OF NEW YORK, N. Y., A CORPORATION OF NEW YORK.

WRIST-WATCH-STRAP ATTACHING MEANS.

Application filed December 21, 1927. Serial No. 241,661.

This invention relates to an improved construction of wrist watch strap attaching means and has for its object to provide in a strap end members which are arranged to be rigidly attached to opposite sides of the watch case to set at an incline to the plane of the face of the watch.

A further object of the invention is to form these end members each with a body portion having a top wall and side walls and providing a bracing plate with inturned edge walls fitting between and secured to the side walls of this end member and providing a hollow center portion in the abutting surface of the end member to receive the projecting attaching eye member on the watch case to which this end member may be attached by a locking pin to dispose these end members on a downwardly inclined angle to the plane of the face of the watch.

With these and other objects in view, the invention consists of certain novel features of construction, as will be more fully described, and particularly pointed out in the appended claims.

In the accompanying drawings:

Fig. 1 is a face view of the watch showing my improved watch strap with its end members secured to opposite sides thereof.

Fig. 2 is an edge view of the watch showing the attaching eye members on the opposite sides thereof.

Fig. 3 is a plan view of one of the end members.

Fig. 4 is a view of the underside of one of the end members.

Fig. 5 is a perspective view showing the brace plate detached from the end member.

Fig. 6 is a view of the underside of the end member showing the brace plate attached thereto.

Fig. 7 is a section on line 7—7 of Fig. 6 showing the brace plate as secured in the end plate.

Fig. 8 is a sectional view of the end member showing the same set at an angle and rigidly attached to the watch case.

Fig. 9 is a section on line 9—9 of Fig. 8 showing the end member as pinned and so rigidly secured to the watch case.

Fig. 10 is a side elevation showing the

wrist watch strap with end members secured at a downwardly inclined angle to opposite sides of the watch case.

It is found in practice of advantage to provide a watch strap with metal end members each of a configuration and finish to harmonize with that of the watch case and so shaped as to present the appearance of being a part of the watch case as such a construction imparts to the watch and strap a higher artistic value than where the end members do not abut or set close against the watch case and which, therefore, cannot present the continuity of shape presented by my improved construction. To accomplish this result in a simple and effective way, I have formed one of the extremities of each of these end pieces with its walls disposed at an incline to the plane of the end piece and I have provided a central opening in the end of this end piece to receive the eye member of the watch whereby the end member may be secured to the watch case by forcing a locking pin through the walls of the end piece and through the eye on the watch case; and the following is a detailed description of the present embodiment of my invention and showing one means by which these advantageous results may be accomplished:

With reference to the drawings, 10 designates the watch case which may be made in any suitable form and to this watch case I have secured attaching eye members 11, the length of which is preferably less than the width of the end member so as to fit between its end walls.

The watch strap 12 may be made in any suitable form and material, the essential feature being that this strap is provided with end members 13, the extremities of which are attached to set rigidly against the side walls 14 of the watch case. These end members each comprises a body portion having a top wall 15 and side walls 16, and in order to provide a more extended bearing surface on the extremity of the end member and to also support and reinforce the stock of the body member, I have provided a brace plate 17 which is formed of stock somewhat heavier than that of the body portion. This brace plate is provided with

side flanges 18 which fits snugly between the side walls 16 of the body member, and the body of the plate itself is set on an angle to the plane of the body member to better serve as a brace and reinforcement of the stock of the body. This brace plate is then secured in position by being soldered therein. The side walls 16 of this body member 15 together with these side flanges 18 of the brace plate 17 are pierced as at 19, see Fig. 7, to receive the lock pin 20, see Figs. 8 and 9, the end walls of this end member are then cut or shaped to set on an incline to the surface of its body portion and by this arrangement of the brace plate with its side flanges a central opening 21 is provided within the outline of these walls and flanges which opening is designed to receive the eye member 20 on the watch so as to permit this 20 end member to be set with its extremity abutting against the side wall of the watch case and when pinned into position by the pin 20 is securely locked to set at a downwardly inclined angle to the plane of the 25 face of the watch. My improved watch strap with its especially constructed end members rigidly attached to opposite sides of the watch case presents the appearance of being a part of the case itself and also 30 presents a continuity of shape and artistic appearance not found in the usual detachable watch hook; also this construction eliminates the possibility of accidental detachment from the watch.

35 The foregoing description is directed solely towards the construction illustrated, but I desire it to be understood that I reserve the privilege of resorting to all the mechanical changes to which the device is 40 susceptible, the invention being defined and limited only by the terms of the appended claims.

I claim:

45 1. A wrist watch strap having metal end members each comprising a body portion with top and side walls, a brace plate having inturned edge walls fitting between and secured to the side walls of the end member, the end bearing surfaces formed by the 50 combined walls of said body member and brace plate being set on an incline to the plane of the body, and said end walls and edges in outline forming a hollow center portion for the reception of the engaging 55 eye on the watch case, and means in said body for securing it rigidly to the watch

case to set on an incline to the face of the watch.

2. A wrist watch strap having metal end members each comprising a body portion with top and side walls, a brace plate having inturned edge walls fitting between and secured to the side walls of the end member, said brace plate being set in the body member at an angle to the plane of its top plate, the end bearing surfaces formed by the combined walls of said body member and brace plate being set on an incline to the plane of the body, and said end walls and edges in outline forming a hollow center portion for the reception of the engaging eye on the watch case, the side walls of said brace plate member being pierced to receive a lock pin to extend through an eye in the watch case to rigidly secure said end members to the case on an incline to the face of the watch. 75

3. A wrist watch strap having an end member comprising a body portion with top and side walls, and a brace plate having inturned edge walls secured to the side walls of the end member and its body between the inturned edge walls disposed at an angle to the top wall of the said end member. 80

4. An end member for wrist watch straps comprising a body portion with top and side walls, the front edges of which are inclined inwardly from the top wall, and means for reinforcing the open end of the 90 said end member including a brace plate having inturned edge walls secured to the sides of the said member and its body between the said inturned edge walls forming a bottom at the front of the said end member. 95

5. An end member for wrist watch straps comprising a body portion with top and side walls, the front edges of which are inclined inwardly from the top wall, and means for reinforcing the open end of the 100 said end member including a brace plate having inturned edge walls secured to the sides of the said member and its body between the said inturned edge walls forming a bottom at the front of the said end member, the front edges of the said brace plate being inclined to correspond with the front edges of the said end member. 105

In testimony whereof I affix my signature.

AUGUST F. KRAEMER.
